UNITED STATES PATENT OFFICE.

ALEXANDER PATTON, OF JEANNETTE, PENNSYLVANIA.

SCREEN-DOOR.

1,121,756.

Specification of Letters Patent. Patented Dec. 22, 1914.

Application filed July 27, 1914. Serial No. 853,437.

To all whom it may concern:

Be it known that I, ALEXANDER PATTON, a citizen of the United States of America, residing at Jeannette, in the county of Westmoreland and State of Pennsylvania, have invented certain new and useful Improvements in Screen-Doors, of which the following is a specification.

The present invention relates to improvements in screen doors, and is designed especially to provide a collapsible or knock down door, that may be compactly arranged for storage purposes.

The primary object of the invention is to provide a sectional hinged door which is furnished with simple and inexpensive means by which the door sections may be held in rigid relationship when the door is performing its usual functions, but which may be knocked down and packed into small compass in order that it may be stored away without occupying much space.

The invention consists in a screen door made up of foldable sections, and a member adapted to engage all of these sections and hold them in rigid relationship, as will be more specifically set forth in the following specification and claim.

In the accompanying drawings I have illustrated one complete example of the physical embodiment of my invention constructed according to the best mode I have so far devised for the practical application of the principles of the invention.

Figure 1 is a plan view of a door constructed according to the principles of my invention. Fig. 2 is an edge view of the door of Fig. 1. Fig. 3 is a perspective view showing the sections of the door folded upon themselves so that the door may be stored away in small compass. Fig. 4 is a perspective view of a batten which is employed to hold the door sections in rigid relationship.

In the preferred embodiment of my invention, as shown in the drawings, I have illustrated the door as a screen door, but it will be understood that other types of doors may be employed in connection with my invention if desired, and I do not wish to con-

fine the description and claim of my invention herein to a screen door.

In Fig. 1 the door is shown in operative position, and it will be seen that it comprises the two lower panels or sections 1 and 2 which are hinged together at 3—3. Two upper sections 4 and 5 are also hinged at 6—6, and the section 4 is hinged to the section 2 at 7—7, but it will be observed that the section 5 is not hinged to the section 1.

To hold all of the sections in rigid relationship with each other, I employ a batten or strip of wood 8 which is perforated at 9 for screws 10, and by means of these screws 10 the batten is secured to each one of the four sections 1, 2, 4, 5, as clearly seen in Fig. 1.

The door is hung upon hinge members 11 as usual, and performs all the functions of any other screen door. The batten 8 which, as before stated, is secured to each one of the four door sections, braces all of the sections and holds them fixed so that the door, as constructed according to my invention, is as rigid and inflexible as the usually constructed door. But in addition to these features the door possesses the meritorious feature of being capable of packing in small space.

In Fig. 3, the door sections are shown in folded position. After the screws 10 have been removed and the batten 8 displaced, the sections may be folded upon their respective hinges. Thus, the section 1 is folded over on top of section 2. Section 5 is folded over on top of section 4, and then the two sections 4 and 5 are folded under in Fig. 1, and on to the under side of section 2, and then the folded door has the appearance as shown in Fig. 3, and it may be stored away in the cellar or attic during the winter time when not in use, and it will occupy but comparatively little space.

From the above description taken in connection with my drawings it is evident that I have provided a screen door which possesses the meritorious features as pointed out as the objects of my invention.

Having thus fully described my inven-

tion, what I claim as new and desire to secure by Letters Patent, is:—

The combination in a foldable door made up of four sections the sections of the upper pair and the sections of the lower pair of said sections being hinged together on a vertical axis, one section of the upper pair of sections being hinged to one of the lower sections to swing on a horizontal axis, a

single horizontally extending batten, and 10 means for attaching said batten to all of said sections.

In testimony whereof I affix my signature in presence of two witnesses.

ALEXANDER PATTON.

Witnesses:

WILLIAM HAWKS,
ROBERT JOHNSON.
